United States Patent Office

Des. 185,496
Patented June 16, 1959

185,496

FLASHLIGHT

John V. Hansen, Madison, Wis., assignor to The Electric Storage Battery Company, Philadelphia, Pa., a corporation of New Jersey

Application April 1, 1958, Serial No. 50,279

Term of patent 14 years

(Cl. D48—24)

FIG. 1

FIG. 2

FIG. 3

FIG. 4

Figure 1 is a side elevation of a flashlight showing my new design;

Figure 2 is a perspective view taken from the front and above;

Figure 3 is a perspective view taken from the rear and above;

Figure 4 is a fragmentary sectional view taken on the line 4—4 of Figure 2.

While only one side of the flashlight of my invention is shown, it should be understood that the opposite side not shown is identical.

I claim:

The ornamental design for a flashlight, as shown and described.
